UNITED STATES PATENT OFFICE.

WILLIAM ALEXANDER FRASER, OF GEORGETOWN, ONTARIO, CANADA.

FLUSHING-TANK.

1,110,432.

Specification of Letters Patent. Patented Sept. 15, 1914.

Application filed November 29, 1912. Serial No. 734,024.

To all whom it may concern:

Be it known that I, WILLIAM ALEXANDER FRASER, of the town of Georgetown, in the county of Halton, in the Province of Ontario, Canada, have invented certain new and useful Improvements in Flushing-Tanks, of which the following is the specification.

My invention relates to the improvements 10 in flushing tanks, and the object of the invention is to provide an open flushing tank in which the intake valve is closed by the pressure behind it contrary to the usual practice, in other words the valve is located 15 between the point of pressure and the seat instead of the seat between the point of pressure and the valve and thus the pressure serves to seat the valve to shut off the supply.

20 A further object is to dispense with any float to finally close off the water.

Another object is to provide a ball of maximum durability to close off the water passing through the flushing pipe.

25 A still further object is to simplify and cheapen the flushing tank generally.

My invention consists of an inlet pipe having an upper elbow forming a valve chamber, a ball and orifice at the bottom of the 30 chamber, a lever to shift the ball operated from the float on the end of the arm attached to the outer end of the fulcrum of the lever, a flushing pipe extending through the bottom of the tank and provided with 35 a suitable yielding seat, a ball valve of comparatively heavy material normally located on the seat, a tipping cage fulcrumed on the top of the flushing pipe, a rod extending through the arm of the float and provided 40 with a stop below the arm and connected at the top to the operating crank to which the pull is affixed, the parts being otherwise constructed and arranged as hereinafter more particularly explained.

45 Figure 1 is a sectional view of an open flush tank provided with my improvements. Fig. 2 is a perspective detail of the flushing pipe and cage lever thereof.

In the drawings like letters of reference 50 indicate corresponding parts in each figure.

A is the flushing tank.

B is the inlet pipe for the water, which extends through the bottom of the tank and is provided with an elbow B¹ having at the 55 bottom a screw plug B² through which ex-

tends an orifice B³ having at the top an annular seat B⁴ upon which rests the ball valve C.

D is the shifting lever having a suitable spindle D¹ and an enlarged upper end D². 60

E is the screw plug, which is fitted into the end of the elbow and F is a spiral spring extending between the enlarged end D² of the shifting lever and the screw plug.

By manipulating the screw plug the pressure of the spring may be regulated.

G is an arm rigidly connected to the end of the fulcrum spindle D¹ of the shifting lever and having located at the opposite end a float H.

I is a flushing pipe, which extends through the bottom of the tank and is provided with a suitable annular seat I¹ of the yielding material.

I² is a ball valve.

J is a cage lever pivoted on the pins J¹ at the top of the flushing pipe and having a small end connected by a rod K to the bell crank L on the spindle L¹ near the top of the flushing tank. The rod is provided 80 with an operating arm on the outside as indicated in dotted lines to which may be connected the pull.

K¹ is a stop located on the rod K below the sleeve K² secured on the arm G. A stop 85 may be located also above the sleeve K² if desired to make the device automatic.

M is a sanitary device communicating by a pipe M¹ to the bottom of the tank and by a pipe M² to the flushing pipe. The sanitary 90 device is of a type, which I have described in concurrent applications and need not be further referred to.

Having now described the principal parts involved in my invention I shall briefly describe its operation.

Upon the pull being operated the bell crank L pulls up on the rod K and tilts the cage lever J on its pivot and throws back the ball allowing the water to pass downwardly through the flushing pipe. The float now will fall and thereby allow the shifting lever to open the ball valve and allow the water to come through the inlet pipe B and orifice B³ into the tank. The 100 movement of the arm and float will be controlled by the stop K¹, so as to give a definite movement to the shifting lever and the ball valve C.

The pressure of the water passing through 110

the inlet pipe will serve to close the ball valve as soon as the lever is shifted back into the normal position shown in the drawing by reason of the float. As soon as the 5 float falls sufficiently low, of course, the ball valve I^2 is thrown back on its seat on the top of the flushing pipe, this movement occurring previously to the restoring of the ball valve C to its closed position.

10. As herein before described a stop may be provided above the sleeve K^2 in order to make the supply of the inlet water and the flush automatic.

15. It will be readily understood that by adjusting the arm G of the float on the end of the fulcrum pin of the shifting lever for the valve C , that the quantity of water admitted for the flush may be regulated in quantity as desired.

20. In the drawings I have shown a spring F between the upper end D^2 of the lever D and the plug E , but it will, of course be under-

stood that this spring is only necessary where there is no water works pressure.

What I claim as my invention is—

25. In a flushing tank, the combination with the flushing pipe and inlet pipe the inlet pipe having an elbow at the top forming a valve chamber and an outlet orifice, a ball and seat therefor at the bottom of the valve 30 chamber, of a shifting lever pivoted on a suitable fulcrum pin and an arm connected to said pin and having a float thereon, said shifting lever and valve being interposed between the pressure or intake end of said 35 inlet pipe and said seat, a passage leading from the upper end of said chamber, an adjustable plug in said passage, and a spiral spring disposed between the upper end of said lever and said plug.

WILLIAM ALEXANDER FRAZER.
